COLLAPSIBLE ROOF UNIT

Charles Burwell Kerrins Van Norman,
Vancouver, British Columbia, Canada

Application April 1, 1944, Serial No. 529,116
In Canada March 31, 1943

3 Claims. (Cl. 108—1)

This invention relates to a collapsible roof unit.

An object of the present invention is the provision of a complete roof unit which may be prefabricated and shipped in collapsed condition to the site for erection.

Another object is the provision of a roof unit which will collapse into a neat and compact bundle for shipment and storage.

Another object is the provision of a relatively large roof unit which may be erected in a very short time with a minimum of labour.

A further object is the provision of a large collapsible roof unit capable of being handled and erected by two men.

A still further object is the provision of a collapsible roof unit, including ceiling panels, which spans the full width of the building.

Yet another object is the provision of a unit of the nature described which gives the walls of the building adequate support.

With these and other objects in view, the present invention consists essentially of a collapsible roof unit comprising a pair of roof panels hingedly connected together at their adjacent sides, said panels being adapted to lie at an angle to each other to form a peaked roof, a depending web hingedly mounted on each end of each panel, the ends of adjacent webs abutting when the panels are peaked, means for connecting the abutted ends of the webs, a ceiling panel hingedly mounted on the outer side of each roof panel normally extending inwardly toward the ceiling panel of the other roof panel, and means for rigidly connecting the adjacent ends of the ceiling panels, as more fully described and illustrated by way of example in the following specification and the accompanying drawings, in which

Figure 1 is an end elevation of the collapsible roof unit,

Figure 2 is a fragmentary vertical section through the unit,

Figure 3 is a plan view,

Figure 4 is a view of the top of the ceiling panels,

Figure 5 is a section taken substantially on the line 5—5 of Figure 1,

Figure 6 is an enlarged section view taken substantially on the line 6—6 of Figure 1.

Figure 7 is a diagram illustrating how the unit is folded, and

Figure 8 is a vertical sectional view through the webs of two adjoining units.

Referring more particularly to the drawings, 10 and 11 are two roof panels hingedly connected

together at their adjacent inner sides by hinges 12. These panels are relatively short in comparison to their widths, the ends and sides thereof being indicated by the numerals 13 and 14, respectively, see Figure 3. Each panel may consist of a single piece of wood having a plurality of stiffeners 15 extending longitudinally thereof on its under side, as shown, or it may be constructed in any other suitable manner. When 10 in use, these roof panels lie at an angle to each other to form a peaked roof, as shown in Figure 1. At the outer sides 14 of the panels, supports 16 depend downwardly and these supports are substantially vertical when the panels are in their 15 peaked position. Ceiling panels 17 and 18 of approximately the same length as the roof panels, are connected at their outer sides by hinges 20 to the inner surfaces of the supports 16. The ceiling panels extend inwardly in a 20 horizontal plane until they meet each other. These panels have longitudinal stiffeners 21, transverse stiffeners 22, and end stiffeners 23 on their upper surfaces. The end stiffeners extend from side to side of the panels and the inner ends 25 of the stiffeners of one panel abut against the corresponding ends of the stiffeners of the other panel. Connecting links 24 are secured to the end stiffeners of one panel and overlap the end stiffeners of the other panel, said links and stiffeners being removably secured together in any suitable manner, such as, by means of bolts 25.

Each roof panel has a web 30 mounted thereon by hinges 31 which normally projects downwardly from each end thereof. These webs preferably are wider at their inner ends than at their outer ends, so that actually they taper outwardly. These webs have longitudinal stiffeners 32 and 33 extending along their upper and lower edges, respectively, on both their inner and outer 40 surfaces. When the roof panels are in their peaked position, the inner ends of the adjacent webs abut against each other, while the stiffeners 33 of one web extend along each side of the other web and are removably secured thereto in 45 any suitable manner, such as as by means of bolts 34. While the webs have been shown as single panels, it will be understood that they may be constructed in any other desired manner.

A plurality of hangers 35 are secured to and 50 extend downwardly from the inner surface of each web and are pivotally connected to the ceiling panel therebeneath by pivots 36. These hangers are made in two sections which are connected together substantially midway between the ends thereof by pivots 37. A plurality of

braces 38 are connected by hinges 40, see Figure 6, to the inner stiffener 33 of each web 30, and are pivotally connected at their opposite ends to the adjacent roof panel by means of pivots 41 which extend through said braces and stiffeners 15. These braces are of the type which consist of two parts pivotally connected by a pivot 42 so that the braces may break in the centre to permit the webs to be folded against the underside of the roof panel, and which lock in their extended positions in any well-known manner.

Figure 8 shows the position of the adjacent webs of two separate units which have been brought together. The outer stiffeners 32 of each web are provided with corresponding tongues 43 and recesses 44, while the outer stiffeners 33 are also provided with corresponding tongues 45 and recesses 46.

Figure 1 shows a complete unit ready to be moved into position. The ceiling panels 18 are provided with longitudinal openings 47 which are adapted to receive the side walls of a building. A plurality of these units are mounted on the walls end to end to provide a complete roof. When mounted in this manner the tongues 43 and 45 of the stiffeners of one unit fit into the corresponding recesses 44 and 46 of the next unit. A suitable mastic may be inserted in the spaces between the roof panels of the adjacent units, and if desired, a cover 48 may be placed on this joint.

This unit may be completely manufactured and assembled in the factory, with the exception that the bolts 25 and 34 are not put in place. The webs 30 may be folded against the inner surfaces of the roof panels 10 and 11, the breaking of the braces 38 permitting this movement. As the webs are folded up, the upper sections of the hangers 35 move therewith and the lower sections, pivoting about the pivots 37, move upwardly and draw the ceiling panels 17 and 18 against the folded webs. Then the roof panels 10 and 11 are folded upwardly with their outer surfaces against each other to make a compact and complete bundle. Figure 7 diagrammatically illustrates the unit as it is being folded up.

When the unit is in use, the longitudinal stiffeners 23, which are connected by bolts 25, prevent the outward movement of the walls of the building, while the abutting ends of the webs 30 prevent the inward movement thereof. These webs brace the roof panels throughout their width, and they support the ceiling panels through the hangers 35. These units are very light in comparison to their strength and size and large units may easily be handled by two men so that they may be erected in a very short

time with a minimum of labor. This advantage is obtained by the fact that the units are completely prefabricated and it is only necessary to unfold them at job and to put the bolts 25 and 34 in their proper places. When in place these units provide not only a roof but a ceiling for the room below them, and yet each unit will collapse into a very small bundle so that it takes up a minimum of space during shipment and storage.

The size of these units are controlled by the requirements, and, of course, the size of the folded bundles will depend upon the unit. For example, a unit which is 25 feet 5 inches wide and 4 feet long when set up, will collapse into a neat rectangular bundle 13 feet 6 inches by 4 feet by 12 inches.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

I claim:

1. A collapsible roof unit comprising a pair of roof panels hinged together at their adjacent sides, said panels being adapted to lie at an angle to each other to form a peaked roof, a depending web hingedly mounted on each end of each panel, the ends of adjacent webs abutting when the panels are peaked, means for connecting the abutted ends of the webs, a ceiling panel hingedly mounted on the outer side of each roof panel normally extending inwardly toward the ceiling panel of the other roof panel, and means for rigidly connecting the adjacent ends of the ceiling panels.

2. A unit according to claim 1 in which a plurality of hangers are provided for supporting the ceiling panels throughout their width from the roof panels, each of said hangers being formed in two sections pivotally connected together at approximately the middle of the hanger, each hanger being connected to a web at its upper end and pivotally connected to a ceiling panel at its lower end.

3. A unit according to claim 1 in which a plurality of braces are provided for retaining the webs in vertical position in relation to the peaked panels, each of said braces being pivotally connected together at approximately the middle of the brace, each brace being pivotally connected to a roof panel at its upper end and to a web at its lower end.

CHARLES BURWELL KERRINS
VAN NORMAN.
